IRA H. SPENCER, OF HARTFORD, CONNECTICUT, ASSIGNOR TO THE SPENCER TURBINE CLEANER COMPANY, OF HARTFORD, CONNECTICUT, A CORPORATION OF CONNECTICUT.

DEVICE FOR COLLECTING AND SEPARATING DUST.

1,114,060.

Specification of Letters Patent.

Patented Oct. 20, 1914.

Application filed November 22, 1907. Serial No. 403,319.

To all whom it may concern:

Be it known that I, IRA H. SPENCER, a citizen of the United States, and a resident of Hartford, in the county of Hartford and 5 State of Connecticut, (whose post-office address is Hartford, Connecticut,) have invented certain new and useful Improvements in Devices for Collecting and Separating Dust, of which the following is a full, 10 clear, and exact description, whereby any one skilled in the art may make and use the same.

The invention relates to an apparatus for separating dust, dirt or like material and air 15 drawn in through suitable connections and for depositing said dirt.

It relates more particularly to a suction apparatus having means for effectively separating all deleterious material from the 20 pregnant fluid drawn therethrough.

The objects of the invention are to provide a simple and extremely efficient apparatus for effectively throwing off through centrifugal action and collecting all materials carried in the fluid which is under 25 the influence of the suction apparatus.

A still further object is to provide means for controlling at different points in the apparatus the separation of the material carried in suspension in the fluid from said fluid 30 as it is forced through the apparatus.

A still further object is to provide means for directing the movements of the fluid in a predetermined manner to secure great efficiency of centrifugal action and positive separation, without disturbing dust and dirt 35 already separated from the fluid.

Referring to the drawings: Figure 1 is a side elevation of the device with parts of 40 the casing broken away to better illustrate the construction. Fig. 2 is a cross-sectional view on the line X—X of Fig. 1 indicating the arrangement of the intake and the cleaning tools attached thereto.

45 The invention is applicable to various devices for separating heavy material from air, but as it is of especial advantage in connection with devices for use in suction cleaning such apparatus has been selected for the purpose of illustration and description of my invention herein, in the accompanying drawings, in which the numeral 1 denotes a tubular casing divided into a series of impeller compartments 2 extending from end to end 50 of the casing 1. These impeller compart-

ments are formed by the insertion within the casing 1 of disks 3 which conform as to general contour to the impeller blades 4. The annular disks 3 have upon one face a series of deflectors 5 curving from the inner periphery of the casing 1 to the central opening 6 of the compartment disks 3. The impeller blades 4 extend from impeller disks 7 mounted in front of the curved deflectors 5 and the plates 7 are secured to hubs 8 mounted upon the main shaft 9. This shaft 9 extends from end to end of the casing 1 and is provided with anti-friction bearings 10—11, 60 suitably arranged in headers 12—13 of the impeller casing. The shaft 9 is driven 65 through a pulley 14 by belt 15 and driving pulley 16. The latter is secured to the armature shaft of a motor 17 suitably mounted upon the casing 1. Arranged upon the header 12 and surrounding the 70 bearing 10 is pivoted an arm 18 which is provided with an axle 19, upon which rotates an idler pulley 20.

At the forward end of the casing 1 is arranged a partition 22 having a central inlet 80 opening 23. This inlet opening 23 lies within a tubular shell or guide 24, which is secured thereto and extends toward the header 12. The first impeller compartment 25 is arranged just in the rear of the partition 22, 85 and as the inlet chamber 21 is arranged substantially tangential to the tube 24 all incoming fluid must pass about said tube and through it before entering the first impeller compartment 25. At the forward end of the 90 tube 24 there are mounted blades 26 which are secured to the main shaft 9 through a hub 27 and disk-like plate 28. There are several of these wings or blades 26 arranged at the outer end of the disk 28 in such manner as to overlie the outer end and surface of the tube 24. In fact, the blades 26 revolve in an annular compartment 29 formed between the tube 24 and the inner periphery of the impeller casing 1. Arranged at one side 95 of the annular chamber 29 is a receiver casing 30 connected with the main casing 1 and provided with a cylindrical removable drawer 31. This drawer 31 acts as a receptacle to receive particles of material thrown off from the fluid as it passes through the annular chamber and enters the tube 24.

The direction of the fluid is as indicated by the arrows, first through the inlet opening, 110

then about the annular chamber 29 where a rapid whirling movement is given to it by the blades 26, then through the interior of the tube 24 and inlet opening 23 to the fan casing. It will be understood that the fluid, no matter how heavily impregnated, will be swirled about the annular chamber 29 and the heavier particles carried in said fluid will be deposited in receptacle 31.

16 The fluid after passing through the tube 24 and the fan casing is subjected to the action of the impeller 32 that is not backed up by one of the disks 3 having curved blades 5, but that runs in an annular chamber 33.

15 This chamber 33 is formed by a tubular extension 34, having a less diameter than the inner walls of the casing 1 and connected thereto by a web 35.

20 Centrally arranged with reference to the disk 36^a of the last impeller 32 and secured to said disk is a tubular extension 36 which has a diameter less than the tubular casing 34 and provides an annular chamber 37, through which the fluid with its impregnating material must pass as it is driven off by the impeller 32. Opposed to the outer end of the annular chamber 37 formed by the tubes 34 and 36 is a wall 38, having a central opening 39 of much less diameter than 25 that of the impeller or the annular chamber 37. When a positive retarding screen or collector is used, this opening 39 connects with the interior of the casing for said positive collector, otherwise the exhaust is connected 30 directly with the chamber 40 formed intermediate the wall 38 and the header 13 of the casing 1.

40 As shown in Fig. 1 there is an upwardly extending casing 42 preferably mounted upon the casing 1 and connecting therewith. This casing 42 is provided with a hand-hole 43 and an exhaust opening 44, the latter separated from the casing 42 and the casing 1 by a cylindrical screen 45. This screen is 45 suspended at its upper end by suitable loops 46 and at its lower end is held in place within a tapered neck 47. This neck 47 extends upwardly and inwardly from a plate 48 which divides the casing 42 into a receiving 50 compartment 49 and an exhaust compartment 50. The latter is of course freely connected with the exhaust opening 44, while the former is connected with the interior of the casing 1 through the compartment 40 and opening 39. The lower end of the screen 45 is provided with a ring 51 of smaller diameter than the inner end of the neck 47. Thus the screen is prevented from rising when subjected to the tension of the passing 55 fluid.

60 The tubular projection 34 being of less diameter than the casing 1 provides an annular chamber 52 which connects with a receiver 53 arranged to be inserted in and removed from the receiver compartment 54.

This compartment 54, as in the case of the compartment 30, is transversely arranged with reference to the casing 1 and receives all particles of material which pass through the various impeller compartments and are 70 finally thrown off by the centrifugal action of the moving fluid induced by the impeller 32.

It has been found that the fluid moved by the impeller 32 is so rapidly whirled through the smooth annular passage 37 that all the appreciable impregnating material is thrown off into the annular chamber 52 where, continuing to swirl it finds its way to the collector or receiver 53. It will be 80 noted that the opening 39 is of a much less diameter than either of the annular chambers 37 or 52, and thus the vortex of the slowly moving, though rapidly whirled, fluid is adjacent to the center of the shaft 9. With this arrangement practically pure fluid 85 is passed through the opening 39.

From the description heretofore given it is apparent that the fluid, more or less completely impregnated, is first swirled through 90 the annular chamber 29, being brought into said chamber by the suction induced by the impellers and rapidly whirled about said chamber by the blades 26. Thus the first action is to centrifugally separate all of the 95 heavier particles borne in the fluid. From the very nature of the device, the air moves at a comparatively slow rate through the impeller casing 1, and particularly, when the positive screen 45, is employed, its movement is much retarded as to exhaust speed when passing from the last impeller 32. This condition compels the rapid whirling of the fluid adjacent to the exhaust side of the apparatus by the impeller 32, and what 100 little impregnating material is borne in the fluid is then thrown off by direct centrifugal action into the receiver 53.

From the above it is apparent that the apparatus comprises one or more distinct provisions for inducing a direct whirling or centrifugal action of fluid for expelling material carried therein. 110

In the operation of the device the separating action and collection of the separated 115 material will be as effective, whether the apparatus is operated to a minimum or maximum extent, with respect to the amount of the fluid passed therethrough.

Obviously, the details of the mechanism 120 might be varied to a considerable extent without departing from the spirit or intent of the invention, and the invention is not therefore limited to a device made in exact accordance with that herein shown and described. 125

What I claim as my invention and desire to secure by Letters Patent is:

1. In an apparatus for collecting and separating dust, a case, a cylindrical tube con- 130

stituting a passage within the case, the latter having a tangentially arranged inlet opening and an outlet opening located on diametrically opposite sides of the tube, a cap overlapping the end of the tube at one side of said openings but permitting entrance of air thereinto, and means for rotating the cap.

2. In an apparatus for collecting and separating dust, a case, means for causing a flow of air through said case, a cylindrical tube constituting a passage within the case, a cap closely fitting the end of the tube and the

sides thereof but permitting the entrance of air thereinto, said case having an opening through its wall located opposite the edge of 15 said cap whereby flow of air directly into the passage between the cap and tube is insured, said case having a second opening through its wall into a dust receptacle, the dust receptacle, and means for rotating the cap.

IRA H. SPENCER.
